ABRASIVE THROWING OR IMPELLING APPARATUS

Louis D. Peik, Cleveland, Ohio, assignor to The American Foundry Equipment Company, New York, N. Y., a corporation of Delaware

Original application August 14, 1933, Serial No. 685,025. Divided and this application March 27, 1940, Serial No. 326,287

2 Claims. (Cl. 51—9)

My invention relates to abrasive throwing or impelling apparatus of the centrifugal type and its primary object is to generally improve and render such abrasive throwing or impelling apparatus more effective and efficient for the work intended and to have long life in operation without appreciable or serious wear or abrasion of the chief operative parts thereof, and hence to provide an improved centrifugal machine for effectively applying abrasive material for the intended purpose at a minimum cost for apparatus and abrasive material employed in a given operation. This application is a true division of my copending application Serial No. 685,025, filed

15 August 14, 1933.

Heretofore it has been proposed to employ centrifugal machines for forcibly throwing or impelling granular materials as sand for cutting and engraving or polishing on stone, metal, glass and other hard substances.

The improved apparatus embodying my invention is primarily designed for forcibly throwing or impelling granular abrasive materials as sand and the like for cleaning and polishing metallic castings as they come from the foundry molds; and in centrifugal machines heretofore employed for this and analogous granular abrasive polishing, cutting and engraving operations on hard substances, bladed rotary centrifugal machines have been devised throwing the abrasive material peripherally and tangentially from the rotor, direction being given to the discharged material by means of shields covering a part of the periphery of the impeller or rotor, thus leaving a part of the discharged material only free for the most effective discharge and polishing or cutting action upon the work in hand, with the resulting effect that a large part of the granular material forcibly passing from the periphery of the rotary impeller tangentially and a high cutting or abrading velocities wastes itself by initially contacting such shields and wearing such shielding apparatus so rapidly as to require distressingly frequent and expensive replacements of such parts, wasting much power, and if not shielded, abrasive also may be wasted or dissipated.

Furthermore, in the known centrifugal machines for throwing or impelling abrasive, the action of the abrasive upon the blades or discharge passage walls of the centrifugal rotors have by reason of the high velocity of the rotors and the friction of the abrasive passing thereover to the periphery and points of tangential discharge of the abrasive, caused rapid destructive wear upon the impeller blades or discharge-de-

vices rendering the rotors exceedingly short lived and requiring such frequent and expensive replacements as to render such apparatus uneconomical and substantially impractical for the intended purpose.

My invention aims at the construction of a novel and improved abrasive throwing and impelling centrifugal device adapted to directionally and positively control the stream of impelled and tangentially discharged abrasive coming from the periphery of the centrifugal device by effectively limiting and confining the discharge to a predetermined sector or portion of the periphery of the centrifugal device.

It is a further object of my invention to provide in an improved centrifugal abrasive throwing and impelling device of the described character, improved, adjustable abrasive discharge controlling means whereby the predetermined and limited effective discharge sector of the device may be shifted at will with respect to the periphery thereof to adjustably control the direction of the discharge stream in relation to the periphery of the centrifugal machine.

Other objects will appear from the following description directed to the preferred embodiment of my invention as depicted in the accompanying drawings forming a part of the specification, the features of novelty being set forth in the appended claims.

In the said drawings:

Fig. 1 is an elevation view of my centrifugal machine, the directionally controlled abrasive discharge stream from which is diagrammatically indicated in connection with a sectional fragment of a table or support for articles being polished or abraded.

Fig. 2 is a vertical section taken through the center of the device of Fig. 1 with the fragmentary work support omitted.

Fig. 3 is a vertical section on line 3—3 of Fig. 2 looking in the direction of the arrows.

Fig. 4 is a fragmentary detail section on line 4—4 of Fig. 2 through the rotor of my centrifugal machine, showing in detail the impeller discharge blade locking means.

Figs. 5 and 6 respectively are fragmentary sections showing modified forms of the rotor structure of my improved machine over the form shown in Figs. 1 to 4 inclusive, and being illustrative of modifications of the abrasive discharging portions of the rotor as specifically shown in the sectional view Fig. 3.

Fig. 7 is a fragmentary transverse section showing details of the modification appearing in

Fig. 6 and being taken upon the radially extending section line 7—7, looking in the direction indicated by the arrows.

Fig. 8 is a sectional view of a modified form of 5 a detachably mounted abrasive discharging or delivery blade construction for the rotor.

In the embodiment of my invention illustrated in Figs. 1 to 4 inclusive the rotary part of the abrasive impelling centrifugal machine is 10 mounted or fixed upon a high speed rotatable shaft 10 carried by suitable bearings, not shown, and consists of two circular plates 11 and 12, preferably detachably and concentrically connected together by a plurality of suitable intermediate or spacing members 13 of sector-like 15 form that may be conveniently spaced apart around the peripheries of and between the plates 11 and 12 to form substantially radiating abrasive discharge passageways 18 leading from the 20 central portion to the outer periphery of the composite rotor thus formed, the said plates 11, 12 and the spacing members 13 being firmly but detachably united by a plurality of screw threaded clamping bolts 14 passing through registering 25 openings in these parts and provided with co-operating threaded nuts 15. Plate 11 is provided with a central laterally extending hub portion 16 having a bore centrally of the plate and of the composite rotatory device by which it is firmly 30 affixed or locked to the high speed rotatable shaft 10 by means of locking key or spline 17 fitted into co-operating grooves in said hub and shaft.

My device (Figs. 1 and 2) is shown as provided with an abrasive gravity supply feed pipe, a 35 section of which is designated by reference character 20 and this supply feed pipe section has formed integrally upon the lower, inwardly curved portion thereof a relatively thick circular head or boss 21 serving as a support for the pipe 40 section 20 and being fixed or non-rotatively supported in relation to the rotative parts on the end of the shaft 10 by any suitable supporting means as by a fixed or stationary embracing fork or notch at its extremity adjacent the outer 45 periphery of the pipe 20 and to which the head or boss is fixedly and detachably secured by the headed screws or bolts 23 so that the head or boss with its integrally connected curved feed pipe section 20 and the adjustable stationary feed ring 50 24 carried thereby may be held in relatively stationary co-operative, registering position in relation to the abrasive feed chamber 25 of substantially cylindrical form, the axis of which coincides with the axis of the speed shaft 10 and rotative 55 parts thereon. The feed head or boss 21 is peripherally grooved to receive a ring or bead 26 or other inwardly projecting part or parts on the cylindrical feed ring or band 24, this ring or other inwardly projecting part guiding the rotary adjustments of feed ring or cup 24 and being shown secured to the feed ring by a plurality of screws 27.

To form the feed chamber cavity 25 in which to receive the feed ring or cup 24, the hubbed disc plate 11 is provided on its inner face with a circular depression 28 and the radially arranged spacing members 13, as well as the outer plate 12, are correspondingly formed or cut away to register with the outer circular, peripheral wall of the depression 28, thus completing the contour of 70 the cylindrical feed chamber or cavity 25. The plate 12 is further preferably recessed on its outer side at 29 to accommodate a peripheral flange 30 integral with the feed ring 24 to provide further offsetting or gland-like means for 75 preventing the escape and loss of abrasive mate-

rial around and through the necessary clearance space between the adjustable feeding ring and the high speed rotative parts of the abrasive stream throwing or impelling device.

To afford additional abrasive receiving space within the feeding cavity or chamber 25, the material on the inner side of the block of the head or boss 21 may be recessed as indicated at 35, leaving a curved, continuation nipple or spout 40 of the feed pipe 20 extending axially into the feed chamber so that granular abrasive or other material being impelled may be delivered well on the interior of the feed chamber 25 and adjacent the path of travel of a plurality of radially arranged agitating lugs or projections 36 shown in the 15 present embodiment as being four in number and equally spaced around the axial line of shaft 10 and the feed chamber and being carried on a circular plate 37 having segmental slots 38 by which it may be adjustably secured by screws 39 20 in the aforesaid depression 28 in plate 11 and over the end of shaft 10 which is keyed to plate 11 whereby to permit axial rotative adjustment of the agitating lugs 36 in relation to other parts around the feed chamber 25, and particularly in 25 relation to the abrasive discharge passageways 18.

A further and most important feature of my invention resides in the impelled abrasive stream restricting and directional determining means which is a function of the before described feed 30 ring or cup 24 in its rotative adjustments on the feed pipe carrying head or boss 21 in combination with the rotative impeller comprised in the plates 11, 12 and interconnecting parts, the peripheral wall of the feed ring or cup being provided with the abrasive feed opening 45 (Figs. 1, 2, 3, 5 and 6) through which granular abrasive or particles of other material to be impelled may pass to the respective discharge passageways toward the outer periphery of the rotary impeller. 40 Adjustments of the feed ring to position its abrasive feed opening 45 are permitted by loosening the screw bolts 46 and the binding washers 47 on the feed chamber head 21 whereupon the radial spaced lugs 48 may be engaged by a suitable tool or by hand and the ring rotated to bring the feed opening to any desired rotative position and then fixedly secured and the discharge of the abrasive stream directionally controlled, as may be understood from the foregoing description of the device and by reference to the diagrammatic portion of the view in Fig. 1 in which with the rotary impeller at normal speed the path of travel of an average grade of abrasive granular material is indicated by dotted lines from the 55 discharge feed ring opening 45, spirally as the material emerging from opening 45 enters the adjacent passageway 18 which is specially constructed to avoid as far as possible friction of the abrasive upon and consequent cutting and destructively wearing the walls, this result being secured by trailing or inclining the direction of the passageway walls rearwardly of the direction of 60 rotative travel of the device in Figs. 1 and 2 so that the said walls extend at an angle of 45° or more to the radial line of discharge of the abrasive through the opening 45. The rear wall of each passageway 18 may be further given a rearwardly curved shape as indicated by reference character 50 as a further protection against 65 harmful or cutting frictional engagement with abrasive.

In order that the desired impelling force be imparted to the abrasive particles before dis- 70 75

charge from the rotating device, the direction of the discharge passageways 18 at their outer extremities will be constructed so as to present substantially radially extending surfaces to the abrasive particles, and such angular turn in the passageways will present a frictional contact with the abrasive being discharged substantially tangentially and will be protected by the placement of detachable, specially hardened metallic plates 10 as designated by reference characters 60 (Figs. 2 to 6 inclusive) which may have a thickened transverse rib 61 engaging a corresponding transverse groove in the discharge passage wall, the plates being detachably secured in position by transverse locking, cylindrical headed screws 63 shown in Figs. 2 to 6 inclusive. Each screw 63, as shown more particularly in Figure 4, is provided with a threaded shank portion 63a which screws into a threaded hole provided in the circular side wall plate 11 and a shoulder portion 63b adapted to engage the adjacent side edge of the adjacent wear plate 60 to secure the wear plate in position.

In Figs. 6 and 7 I show a modified form of the impeller in which the spacing members are constructed to provide radial air relief passages 70 leading into discharge passageways 80 corresponding to passageways 18 and these modified spacing members being indicated by reference character 81. A transverse air relief passage 71 communicates with air relief passage 70 and vents through registering openings 12, 73 in rotor plates 11 and 12 respectively. The air relief to the impeller discharge passageways thus provided is highly advantageous in discharging certain forms of abrasive and other analogous materials.

In Fig. 5 I show a further modified form of discharge passageway 90 in which the discharge plates 60 are positioned at an overhang angle to the radial line of the discharge passageway for advantageously throwing modified forms of abrasive and the like and varying the character of the thrown stream, these modified spacing members being indicated at 91.

In Fig. 8 I show a modified form of the effective discharging surface of plates intended to replace plates 60, the same being designated as 95 and having a specially formed, hardened, corrugated throwing surface comprising a plurality of slightly angular elevations 96 arranged on the plates so as to present a succession of slight inclines to the outward travel of the abrasive, each incline followed by an abrupt step-down as indicated at 97. As the abrasive is impelled over the inclined surfaces 96 in passing over the step-down portions 97, an air cushion is formed in the grooves under the particles that protects the material of the plates from the usual and expected abrasion.

From the foregoing description of my invention it will be seen that I have provided improved abrasive impelling means that is capable of directing a controlled stream in any desired direction around the rotor axis, determinable by the described adjustment of the feed ring 24 since it will be seen that when articles to be treated or abraded are placed in a definite location with respect to the machine as, for example, upon the upper surface of the work support, designated by the reference character 98 in Fig. 1, and with the abrasive feed ring opening 45 adjusted to the position indicated in Fig. 1, the abrasive material thrown successively from each of the discharge passageways 18 past the

hardened throwing plates 60 will be restricted to substantially the zone of discharge indicated by the nearly tangentially extending full lines as shown illustratively in Fig. 1, and it will be further noted that this is true of the discharge of the abrasive material from each of the plurality of discharge passageways shown in the present embodiment of the invention as four in number which is the preferred construction since the abrasive material will only be received into each of the passageways 18 as they successively pass the abrasive discharge opening 45; and with the rotative device traveling at operating speed with a given character of abrasive as sand, the path of the material as it moves radially outward in each successive throwing passageway 18 will be substantially as defined by the dotted line indications within the rotatory part so that a complete directional control of the abrasive material is obtained without wastage of material or of power in impelling material in any direction except the desired direction of the stream for accomplishing the work in hand, so that the use of abrasive shielding around the periphery of the rotatory parts and the expense of the same may be dispensed with, and the rotatory parts are furthermore so constructed as to handle the abrasive throughout the operation with the minimum amount of friction or abrading effect upon the parts, except for the delivery discharging plates 60 which may be specially hardened and readily replaced at a minimum expense for renewals, thus attaining a novel limiting and directional effect to the abrasive stream which will be varied at will around the entire periphery of the rotatory device by the described rotative adjustment of the discharge opening 45 of the feed ring 24, thus adapting the machine to a wide range of usefulness in the forceful impelling of a controllable stream of various comminuted or liquid materials and analogous substances, it being understood that the rotation of the agitating lugs 36 on the moving circular plate 37 within the feed chamber will have the effect of presenting the delivered material in the feed chamber to the discharge opening 45 of the feed ring in the various positions of indicated adjustment of the respective parts of the feed ring and the feed chamber agitating means.

In order that the invention might be understood the details of the preferred embodiment have been specifically shown and described but it is not desired to be limited to such details except as specified in the claims, for it will be apparent that persons skilled in the art may resort to various modifications without departing from the purpose and spirit of the invention.

What is claimed is:

1. In a centrifugal machine for throwing abrasive at blasting velocities, a rotatably mounted rotor head embracing a pair of spaced side wall discs, a plurality of blade members positioned between and supported by said discs, said blade members being arranged in circumferentially spaced relationship between said discs and extending inwardly short of the axis of rotation of said discs to provide a central space, each of said blade members presenting an abrasive throwing surface embracing a removable and replaceable wear plate having a lug portion projecting from the bottom face thereof and seated within a corresponding recess in said blade member, and a bolt for holding each of said wear plates in operative position, each of said bolts having a threaded portion extending

into a threaded aperture in one of said side wall discs and a shoulder portion engaging the side edge of the adjacent wear plate.

2. In a centrifugal machine for throwing abrasive at blasting velocities, a rotatably mounted rotor head embracing a pair of spaced side wall discs, a plurality of blade members positioned between and supported by said discs, said blade members being arranged in circumferentially spaced relationship between said discs and extending inwardly short of the axis of rotation of said discs to provide a central space, each of said blade members presenting an abrasive

throwing surface embracing a removable and replaceable wear plate having a lug portion projecting from the bottom face thereof and seated within a corresponding recess in said blade member, and a bolt for holding each of said wear plates in operative position, each of said bolts having a shank portion extending through one of said discs, a threaded portion extending into a threaded aperture in the other disc, and a shoulder portion engaging the side edge of the adjacent wear plate.

LOUIS D. PEIK.
